ATTORNEY

UNITED STATES PATENT OFFICE.

ROBERT R. MCINTYRE, OF FLORENZA, PENNSYLVANIA.

RAILROAD-TIE.

1,198,248.

Specification of Letters Patent. Patented Sept. 12, 1916.

Original application filed April 4, 1916, Serial No. 89,154. Divided and this application filed June 6, 1916.
Serial No. 102,048.

To all whom it may concern:

Be it known that I, ROBERT R. MCINTYRE, a citizen of the United States, residing at Florenza, in the county of Jefferson and State of Pennsylvania, have invented certain new and useful Improvements in Railroad-Ties, of which the following is a specification.

This invention relates to an improved railroad tie and the principal object of the invention is to provide a tie which can be formed of metal and preferably of sheet metal, an improved base and rail supporting structure being provided and also improved means for holding the rail engaging plates in engagement with the tie being provided.

This invention is illustrated in the accompanying drawings, wherein:

Figure 1 is a longitudinal sectional view through the improved tie. Fig. 2 is a longitudinal sectional view through a slightly modified form of the improved tie. Fig. 3 is a transverse sectional view taken along the line 3-3 of Fig. 2. Fig. 4 is a transverse sectional view taken along the line 4-4 of Fig. 1.

The body portion indicated in general by the numeral 10 has an upper wall 11, side walls 12 and end walls 13. The upper wall 30 is depressed adjacent the ends of the body portion to provide the rail seat 14 and the side walls 12 are pressed inwardly to provide pockets 15 into which pass the bolts 16 serving to hold the rail engaging plates 17 in engagement with the body portion 10. These plates 17 which engage the rails 18 may be formed either as shown in Figs. 1 and 4 or as shown in Figs. 3 and 2, the plates shown in Figs. 1 and 4 engaging the bases 40 of the rails with two plates for each side of the rails and in Figs. 2 and 3, a single plate being provided for each side of the rail and provided with countersunk seats 19 for the heads of the bolts 16 and with enlarged heads 17' resembling fish plates and extending along the webs of the rails and provided with openings through which securing bolts 20 may pass to connect adjoining rails.

The base 21 in Figs. 1 and 4 extends the full length of the tie and is provided with end walls 22 and side walls 23, the side walls being pressed inwardly to provide pockets 24 to receive the pockets 15 of the body portion. By means of this structure, the body portion and base will be prevented from

having independent longitudinal movement and thus strain will be lessened upon the end walls 13 and 22. These pockets further permit the body portion to move downwardly without the securing bolts 16 striking and becoming loosened. Pins which are in the form of bolts 25 are carried by the body portion in the rail seats 14 where they will be held in place by the rails 18 and passed through supporting springs 26, the pins serving to hold the springs in place and in the proper position so that when the train passes over the track, the weight of the train will be taken up by the springs.

In the form shown in Figs. 2 and 3, the base is in two sections 27 which have telescoping engagement with the body portion and may if desired be provided with pockets similar to the pockets 24. Bolts or pins 28 similar to the pins 25 are provided and extend from the rail seats 14 through the base sections 27 and pass through springs 29 similar to the springs 26.

What is claimed is:

1. A tie comprising a body portion having an upper wall provided adjacent its ends with struck-in portions forming rail seats, said body portion being provided with end walls and with side walls provided with struck-in portions forming pockets upon opposite sides of said rail seats, rail engaging plates fitting upon the upper wall of said body portion and extending over the rail seats, fasteners passing through said plates and the upper wall of the body portion into said pockets, a base section positioned beneath said body portion and having telescoping engagement therewith, pins extending from the rail seats through the base section, and supporting springs positioned about said pins between said rail seats and base section.

2. A tie comprising a body portion having an upper wall, end walls and side walls, the side walls being provided with struck-in portions forming pockets and the upper wall being provided with rail seats positioned between the pockets, a base positioned beneath said body portion and having end walls and side walls engaging the walls of the body portion, the side walls of the base being provided with struck-in portions forming pockets receiving the pockets of said body portion, rail engaging plates fitting upon said body portion and extending over the rail

seats, fasteners passing through said rail engaging plates and the upper wall of the body portion into said pockets, and resilient supporting means positioned between said base and the upper wall of said body portion beneath the rail seats.

3. A railroad tie comprising a body portion having rail seats and fastener receiving pockets positioned upon opposite sides of 10 said rail seats, a base extending beneath each of said rail seats, resilient supporting means positioned beneath each of said rail seats and engaging the same to yieldably support the body portion, and pins extending front 15 the rail seats through the resilient supporting means.

4. A tie comprising a body portion having side walls provided with struck-in por-

tions forming fastener receiving pockets, rail engaging means resting upon said body portion, fasteners passing through said rail engaging means and into said pockets, a base extending beneath the ends of said body portion and having telescoping engagement therewith, pins extending from said body portion and extending through the base at the respective ends of the body portion, and resilient supporting means positioned about said pins and engaging said body portion to yieldably support the body portion. 20 25 30

In testimony whereof I affix my signature in presence of two witnesses.

ROBERT R. McINTYRE.
